UNITED STATES PATENT OFFICE.

JOHN W. MEAKER, OF DETROIT, MICHIGAN.

VALVE FOR EXPLOSIVE-ENGINES.

Specification of Letters Patent.

Patented Mar. 3, 1914.

1,088,714.

Application filed May 13, 1912. Serial No. 696,816.

To all whom it may concern:

Be it known that I, JOHN W. MEAKER, a citizen of the United States of America, residing at Detroit, in the county of Wayne and State of Michigan, have invented certain new and useful Improvements in Valves for Explosive-Engines, of which the following is a specification, reference being had therein to the accompanying drawings.

10 In the operation of explosive engines, it is desirable, in order to obtain the greatest efficiency, that the inlet and exhaust ports of the cylinders be opened as rapidly as possible. It is also desirable that the valves or like 15 means controlling the ports operate with as little noise as possible and that the driving mechanism for such valves or the like be positive in its action to insure proper timing of the valves in relation to the engine 20 cycle.

This invention relates to explosive engines and especially an arrangement of the valves thereof whereby the inlet and exhaust ports of the cylinders are rapidly uncovered and 25 whereby positive action that is practically noiseless is imparted to the valves by mechanism which insures the proper timing of the valve movement in relation to the piston movements.

30 The invention consists in the matters hereinafter set forth and more particularly pointed out in the appended claims.

In the drawings, Figure 1 is a view partially in side elevation and partially in section, of a portion of a multi-cylinder explosive engine provided with a valve and valve gear that embodies features of the invention; Fig. 2 is a view in transverse section through a pair of motor cylinders; Fig. 3 is a view in vertical section through one 40 of the cylinders on line III—III Fig. 2, the section line II—II on which Fig. 2 is taken being indicated; Fig. 4 is a view in section showing a modification of the device; Fig. 45 5 is a view in section on line IV—IV of Fig. 4; Fig. 6 is a view in detail of an expansion packing member; and Figs. 7 and 8 are views in detail showing the application of the member to a cylinder with a single closure.

The invention as herein shown, is illustrated as applied to an explosive engine having a plurality of cylinders 1 and a main shaft 2 operated by pistons 3 in the cylinders. Each cylinder has an intake port 4 through its wall near the explosion head

and a similar exhaust port 5. An inner annular valve closure 6 is journaled concentrically on the head of the cylinder and is provided with an opening 7 adapted to be 60 brought into successive registration with the ports 4 and 5 when the sleeve is turned. An outer valve sleeve 8 is journaled concentrically on the inner sleeve and is provided with an opening 9 which may be 65 brought simultaneously with the port 7 of the inner sleeve into registration with the ports 4 and 5 of the cylinder successively. The relative areas of the ports 4 and 5 and of the sleeve openings 7 and 9 are so proportioned as to leave the ports 4 and 5 uncovered a sufficient time for the successful 70 operation of the motor, such ports being respectively connected with intake manifold openings, and exhaust manifold outlets in 75 the cylinder wall. For symmetry of arrangement and ease of construction the manifold openings of each pair of cylinders are preferably disposed as shown in Fig. 2 so as to be readily coupled to the manifold. 80

The outer sleeves are positively driven in unison by gears 12 formed on or secured to flanges 13 on the lower portions of the sleeve, the gears of the adjacent sleeves intermeshing and being driven in common by a pinion 85 14 that is geared or otherwise secured to a shaft 15 operated through beveled gears 16 or the like from a counter-shaft that in turn is rotated by any suitable mechanism from the engine shaft. The inner sleeves 6 are 90 likewise provided with driving gears 18 on or secured to flanges 19 on the sleeves, the gears being in train and operated by a driving pinion 20. The latter is secured to a spindle 21 that is operated by a pair of 95 beveled gears 22 or the like that couple it to the countershaft to turn in opposite directions to the spindle or shaft 15. As a convenient detail of construction the shaft 15 may be hollow and form a bearing sleeve 100 for the spindle 21.

In the construction shown the ports 4 and 5 of the cylinder are in the same horizontal plane. It sometimes is advisable to place them in different planes and such 105 construction is indicated in Figs. 4 and 5 in which a cylinder 23 has an intake port 24, and arched or crowned head 25 converging to or forming a guide for gases to an exhaust 26 above the plane of the intake. 110 In such construction an inner sleeve 27 has a port 28 which may be brought into regis-

ter with the port 24 and another port 29 which may be brought into register with the port 26. An outer concentric valve sleeve 30 has a lower intake 31 that is in the plane 5 of and so may be brought to register with the ports 24 and 28, while the upper port 32 in the outer sleeve may likewise be simultaneously brought into registration with the exhaust port 26 of the cylinder and the 10 mating port of the inner sleeve.

In both constructions suitable expansion rings, such as those indicated in Fig. 6, are used to prevent leakage when the ordinary provisions for cooling the cylinder 15 walls and cylinder heads are employed. In preferred form these consist of an inner pair of segmental sections 33 whose corresponding ends are united by cross bars 34, and an outer pair of segments 35, united by 20 ends bars 36. When in place with the end bars on opposite sides of the ports in appropriate channels, they form a perfect seal against the escape of gases around the ports. By this form of construction and the proper 25 disposition of the ports the oppositely rotating sleeves uncover each port in half the time required by a single sleeve and as the ports of the cylinder may be made very narrow the necessary area being obtained by 30 lengthening the ports, it is possible to obtain extremely rapid action of the valves. As the motion of the valves is continuous and not reciprocatory they are practically 35 noiseless in action and the driving gear which is positive is likewise quiet in its movements so that the motor runs with greater freedom from noise than motors of the usual type. Furthermore as there is no 40 pounding or battering of the valves the latter will wear evenly and cannot leak as the packing rings obviate this and are readily removed and repaired as needed without the necessity of regrinding or refilling the valve 45 closures proper.

Obviously, changes in the details of construction may be made without departing from the spirit of the invention and I do not care to limit myself to any particular form or arrangement of parts.

50 What I claim is:—

1. In an explosive engine, a cylinder having a lateral intake and a lateral exhaust port, an inner expansion ring consisting of a pair of segmental sections extending circumferentially around the cylinder wall in 55 grooves thereof from one port to the next with end bars connecting the adjacent end portions of the segments and lying in grooves in the wall adjacent a longitudinal 60 margin of the port, an outer expansion ring having a pair of segmental sections encir-

cling the cylinder wall from port to port in the groove of the inner ring with end bars connecting the adjacent end portions of the sections and lying in grooves each adjacent 65 the other longitudinal margin of a port, and an annular valve closure journaled on the cylinder around the ports, and rings and provided with an opening adapted to register with either port. 70

2. In an explosive engine, the combination with a cylinder having a lateral exhaust port and a lateral inlet port, and an annular valve closure journaled on the cylinder over the ports and provided with an 75 opening that may be brought to register with either of the ports, of means for preventing leakage between the closure and cylinder from the mouths of the ports consisting of a pair of expansion members, the 80 inner one having a pair of segmental sections extending circumferentially of the cylinder from port to port in channels in the cylinder wall with the end portions thereof connected by end bars lying in grooves 85 parallel to the adjacent longitudinal margin of the ports, the outer member having a pair of segmental sections abutting the outer faces of the inner member sections in the channels of the cylinder, the end portions being united by end bars lying in grooves parallel to the other longitudinal 90 margins of the ports.

3. In an explosive engine, a cylinder having a lateral intake and a lateral exhaust 95 port, an inner expansion ring consisting of a pair of segmental sections extending circumferentially around the cylinder wall in grooves thereof from one port to the next with end bars connecting the adjacent end 100 portions of the segments and lying in grooves in the wall adjacent a longitudinal margin of the port, an outer expansion ring having a pair of segmental sections encircling the cylinder wall from port to port in 105 the groove of the inner ring with end bars connecting the adjacent end portions of the sections and lying in grooves each adjacent the other longitudinal margin of a port, a 110 pair of annular valve closures journaled concentrically on the cylinder around the 115 ports and rings and each provided with an opening, these openings being adapted to simultaneously register with either of the ports, and means for independently turning the closures.

In testimony whereof I affix my signature in presence of two witnesses.

JOHN W. MEAKER.
